Primary Examiner — Robert M. Spear

(74) Attorney, Agent, or Firm — Davis & Bujold PLLC;
 Michael J. Bujold(57) **CLAIM**

I claim the ornamental design for an airless sand tire, as shown and described.

DESCRIPTION

FIG. 1 is a front perspective view of an airless sand tire embodying my/our new design;

FIG. 2 is a front elevational view thereof;

FIG. 3 is a left side elevational view thereof;

FIG. 4 is a top, front, left side perspective view thereof;

FIG. 5 is a bottom, left side view thereof;

FIG. 6 is a left side perspective view thereof;

FIG. 7 is a right side elevational view thereof;

FIG. 8 is a rear, right side view thereof;

FIG. 9 is a bottom, right side view thereof; and,

FIG. 10 is top, right side view thereof.
